UNITED STATES PATENT OFFICE.

LEON F. N. BALDWIN, OF PROVIDENCE, RHODE ISLAND, ASSIGNOR, BY MESNE ASSIGNMENTS, TO THE SLAYMAKER-BARRY COMPANY, INCORPORATED, OF CONNELLSVILLE, PENNSYLVANIA.

DEVICE FOR DRYING EXHAUST-STEAM.

SPECIFICATION forming part of Letters Patent No. 653,334, dated July 10, 1900.

Application filed October 19, 1899. Serial No. 734,118. (No model.)

To all whom it may concern:

Be it known that I, LEON F. N. BALDWIN, a citizen of the United States, residing at Providence, in the county of Providence and State 5 of Rhode Island, have invented certain new and useful Improvements in Devices for Drying Exhaust-Steam, of which the following is a specification, reference being had therein to the accompanying drawings.

10 Like letters indicate like parts.

Figure 1 is a view of my invention as seen on line *z z* of Fig. 2. Fig. 2 is a view of the same as seen on line *x x* of Fig. 1.

15 My invention is an apparatus for drying the exhaust-steam from the ports of the cylinder of a steam-engine, and is especially adapted for use in automobile vehicles operated by steam.

20 My invention consists of the combination of a steam-boiler having hot-air flues through it, a chamber above the boiler into which said flues open, a vertical smoke-pipe discharging at both ends and connected with said chamber, a steam-exhaust pipe opening into said 25 chamber, and a perforated plate extending through said chamber, with a tongue projecting into the smoke-pipe, which plate is provided with a series of angularly-inclined baffle-plates extending over the perforations 30 of the plate, as hereinafter particularly described.

In the drawings, A represents a steam-boiler, through which pass the hot-air flues *a a*. These flues open through the top plate *b*. On the top 35 of the boiler A is the chamber B. A steam-pipe C enters said chamber.

40 D is a vertical smoke-pipe open at both ends and connected with the chamber B by a pipe E. A plate F is fastened to the sides of the chamber B and extends nearly horizontal, but somewhat inclined, over the top plate *b* of the boiler and a short distance therefrom. This plate F has a tongue G extending on one side, which is curved at its end and extends through 45 the pipe E and into the smoke-pipe D. The plate F has a series of perforations *c c*, arranged in parallel rows, and over the rows of perforations, respectively, are angularly-inclined baffle-plates H, parallel with each

other and flaring upwardly toward that end of 50 the chamber B where the pipe C opens therefrom. The plates H are fastened to the plate F by the bolts *d d*.

A damper I extends across the smoke-pipe D near its top and is pivotally hung, as shown 55 at *e* in Fig. 1, through a slot on the side of said pipe. The damper I has an arm *m* extending outside of the pipe D, and on the end of the arm is an adjustable weight *n*.

The heat, gas, and smoke pass up through 60 the flues *a* of the steam-boiler A into the chamber B and also through the perforations *c c* of the plate F and are deflected by the baffle-plates H toward the pipe E and are carried by the pipe E into the pipe D, whence they are 65 discharged into the outer air. The pipe C conducts exhaust-steam from the ports of the cylinder of the steam-engine into the chamber B. The plates F and H are heated by the 70 hot air which impinges upon them from the flues *a*, and this heat, together with that which passes through the perforations *c c* of the plate F, dries out the moisture of the exhaust-steam discharged by the pipe C into the chamber B, so that said steam passes out from the pipe D 75 into the external atmosphere in the form of an invisible vapor.

The escape of dense white masses of steam directly into the open air, as is common in the use of steam-operated automobile vehicles, is a serious objection to their travel upon the streets of a city and is very liable to 80 frighten horses, and thus to cause great damage. By the use of my said device this difficulty is avoided.

When the fire is first started in order to 85 make steam in the boiler A, the damper I should be open, so that the smoke will pass out through the upper end of the pipe D, and suitable means should be provided for securing the damper in such position temporarily, such as a hook or similar device; but when 90 the steam has been made such fastening is loosened and the damper is thenceforth automatic. It is so weighted that it is nearly 95 but not quite balanced by the counterpoise *n* upon the arm *m* thereof, and normally extends horizontally across the pipe D on the

inside. A stop on the inside of the pipe prevents the damper I from rising above a horizontal position. The hot air and dry steam will then pass down the pipe D and be discharged from the lower end of said pipe. To facilitate such downward current, the end of the tongue G is curved downwardly, as seen in Fig. 1. Now it may sometimes occur that by reason of the downrush of the steam over the tongue G and through the pipe D to the open bottom thereof a suction or tendency to a vacuum is produced in the lower portions of the chamber B below the plate F and tongue G, which will draw cold air up through the fire-receptacle and the flues a, thus reducing the temperature of the chamber B, as also the steam-pressure in the boiler A. It is to obviate this tendency that the damper I is pivotally hung and weighted, as shown, for when such a condition is reached the suction downward in the pipe D at once draws the damper I down, as indicated in dotted lines in Fig. 1, and air from without rushing in through the top of the pipe D immediately supplies the demand, thus protecting the fire from excessive draft, and as soon as the pressures are equalized the weight n brings the damper I automatically to its normal position again.

30 I claim as a novel and useful invention and desire to secure by Letters Patent—

1. The combination of a steam-boiler having hot-air flues through it, a chamber above the boiler into which said flues open, a pipe entering said chamber and adapted to convey exhaust-steam from a receptacle containing the same, a smoke-pipe and a pipe connecting said chamber with the smoke-pipe, and a plate extending in a direction slightly inclined from a horizontal line, through said chamber a short distance above the upper ends of said flues and located below said steam-pipe, substantially as specified.

2. The combination of a steam-boiler having hot-air flues through it, a chamber above the boiler into which said flues open, a pipe entering said chamber and adapted to convey exhaust-steam from a receptacle containing the same, a smoke-pipe and a pipe connecting said chamber with the smoke-pipe, and a plate having a series of perforations and extending in a direction slightly inclined from a horizontal line through said chamber a short distance above the upper ends of said flues and located below said steam-pipe, substantially as described.

3. The combination of a steam-boiler having hot-air flues through it, a chamber above the boiler into which said flues open, a pipe entering said chamber and adapted to convey exhaust-steam from a receptacle containing the same, a smoke-pipe and a pipe connect-

ing said chamber with the smoke-pipe, a plate having a series of perforations arranged in parallel rows, which plate extends in a direction slightly inclined from a horizontal line through said chamber a short distance above the upper ends of said flues and located below said steam-pipe, and a series of angularly-inclined baffler-plates fastened to said plate and extending over the rows of perforations, respectively, substantially as shown.

4. The combination of a steam-boiler having hot-air flues through it, a chamber above the boiler into which said flues open, a pipe entering said chamber and adapted to convey exhaust-steam from a receptacle containing the same, a smoke-stack open at both ends and a pipe connecting said chamber with the smoke-pipe at a place intermediate between the ends of the smoke-pipe, a plate having a series of perforations arranged in parallel rows, which plate extends in a direction slightly inclined from a horizontal line through said chamber a short distance above the upper ends of said flues and located below said steam-pipe, a series of angularly-inclined baffler-plates fastened to said plate and extending over the rows of perforations, respectively, and a curved tongue extending from said plate through said connecting-pipe and down into the smoke-pipe, substantially as set forth.

5. The combination of a steam-boiler having hot-air flues through it, a chamber above the boiler into which said flues open, a pipe entering said chamber and adapted to convey exhaust-steam from a receptacle containing the same, a smoke-pipe open at both ends and a pipe connecting said chamber and smoke-pipe at a place intermediate between the ends of the smoke-pipe, a plate having a series of perforations arranged in parallel rows, which plate extends in a direction slightly inclined from a horizontal line through said chamber a short distance above the upper ends of said flues and located below said steam-pipe, a series of angularly-inclined baffler-plates fastened to said plate and extending over the rows of perforations, respectively, a curved tongue extending from said plate through said connecting-pipe and down into the smoke-pipe, and a damper across the upper end of the smoke-pipe, pivotally hung at one side of said pipe and provided with an arm and a counterpoise thereon, substantially as and for the purpose specified.

In testimony whereof I affix my signature in presence of two witnesses.

LEON F. N. BALDWIN.
